FLUORESCENT LUMINAIRE FOR STREET LIGHTING

Donald W. Harling, Milwaukee, Wis., assignor to McGraw
Electric Company, Milwaukee, Wis., a corporation of
Delaware

Application January 28, 1955, Serial No. 34,277

Term of patent 14 years

(Cl. D48—31)

FIG. 1.

FIG. 2.

FIG. 3.

Fig. 1 is a side elevational view of a fluorescent luminaire for street lighting showing my new design.

Fig. 2 is a top plan view of the luminaire.

Fig. 3 is an end elevational view taken at either end of the luminaire.

I claim:

The ornamental design for a fluorescent luminaire for street lighting, as shown.
